UNITED STATES PATENT OFFICE.

FELIX TRAMBLAY, OF MILWAUKEE, WISCONSIN.

SUPPORTING DEVICE FOR SLIDING DRAWERS.

SPECIFICATION forming part of Letters Patent No. 740,337, dated September 29, 1903.

Application filed June 9, 1902. Serial No. 110,724. (No model.)

To all whom it may concern:

Be it known that I, FELIX TRAMBLAY, of Milwaukee, in the county of Milwaukee and State of Wisconsin, have invented certain new and useful Improvements in Supporting Devices for Sliding Drawers; and I do hereby declare that the following is a full, clear, and exact description thereof, reference being had to the accompanying drawings, and to the letters of reference marked thereon, which form a part of this specification.

This invention relates to improvements in supporting devices for drawers of filing-cases, desks, and other office or household furniture, and refers more specifically to means for supporting the drawers when fully opened.

The invention consists in the matters hereinafter set forth, and more particularly pointed out in the appended claims.

20 In the drawings, Figure 1 is a perspective view of a fragment of a piece of furniture—such as a desk, filing-case, or the like—showing a portion of the compartment which receives the drawer and also illustrating the 25 drawer in its open position and supported by the devices constituting my invention. Fig. 2 is a horizontal fragmentary section taken through the walls of the drawer-compartment, showing a fragmentary part of the drawer in 30 top plan and the position of the drawer-supporting devices when the drawer is closed. Fig. 3 is a cross-section taken on line 3 3 of Fig. 2. Fig. 4 is a cross-section taken on line 4 4 of Fig. 2. Fig. 5 is a side elevation of one 35 of the supporting-bars constituting part of the drawer-supporting devices. Fig. 6 is an edge elevation of the part shown in Fig. 5.

As shown in said drawings, A designates a fragment of a desk, filing-cabinet, or other 40 piece of furniture having side walls A' A' and a back wall A², constituting a compartment for the drawer.

B designates a drawer of usual form having side walls b b, end walls b' b', and a bottom wall b² and made of a width to fit closely 45 between the side walls A' of the compartment. Said drawer is supported either on runways located at the side walls of the compartment in a familiar manner or, as herein shown, on a horizontal board or plate A³, which constitutes the horizontal partition between the compartment for one drawer and a

compartment for a drawer beneath the same. So far as the construction of the drawer and the compartment for receiving the same is concerned and thus far described said construction may consist of any of the well-known or preferred types.

The improvements constituting my invention consist of devices which are designed to 60 horizontally support the drawer when it is fully opened, whereby access may be had to the rear end of the drawer for consulting papers or other articles located therein, said supporting devices being so constructed and 65 arranged as to firmly support the drawer in its outermost position and prevent the same from falling out or dropping away from its compartment. Said supporting devices consist in general terms of two bars C C, located 70 one on each side of the drawer and occupying and having longitudinal sliding engagement with grooves A⁴ A⁴ in the inner faces of the side walls of the drawer-compartment. Said bars are fitted in said grooves so as to 75 move freely endwise therein, but are held from lateral displacement. One means for effecting this result and which is herein illustrated is to make the grooves of undercut 80 cross-section and to shape the bars so as to fit closely in said undercut grooves. Said supporting-bars are adapted to engage at their outer ends hooks D, attached to the outer faces of the side walls of the drawer, said 85 hooks opening downwardly and the bars entering the same from below. Said bars are made thinner and narrower at their outer ends than at their inner ends, and, as herein shown, the increased thickness of the bars is produced by longitudinally-folding strips 90 c about the rear ends of the main bodies c' of the bars. The larger rear ends of the bars fit closely in the grooves A⁴ in the side walls of the drawer-compartment, thereby establishing the interfitting relation between 95 said parts, which allows free endwise movement of the bars, but prevents lateral displacement thereof. The forward or narrower portions c' of the bars occupy and have freely-sliding engagement with the hooks D, and said outer ends of the bars are provided with short lateral inwardly-extending stop-lugs c², which prevent the hooks from being drawn over the ends of the bars and released there-

from. As herein shown, said stop-lugs c^2 are formed by slitting the end portions of the bars and folding the parts between said slits inwardly. The shanks d of said hooks 5 are offset outwardly, as shown in Figs. 2 and 4, so as to bring the hook portions thereof in line with the narrower outer parts c' of the supporting-bars. Said grooves A^4 of the side walls of the compartment are not made 10 of the same depth from front to rear thereof, but are made shallower near their forward ends, thereby providing in each of said grooves rearwardly-facing shoulders a , as most clearly shown in Fig. 2. The supporting-bars C are provided at their rear ends with outwardly-extending stop-lugs c^3 , which are adapted to engage the shoulders a to limit the endwise movement of the supporting-bars in said grooves A^4 . Said lugs may 15 be attached to or formed on the bars in any suitable manner. As herein shown, they consist of short screw-threaded pins, which engage screw-threaded apertures in said bars. The supporting-bars are inserted endwise 20 through the forward ends of the grooves A^4 before the stop lugs or pins c^3 are placed therein, and when the openings in the rear ends of said bars are thrust past the shoulders a of said grooves said lugs or pins are 25 inserted into said openings. The said shoulders a and the supporting-hooks D on the drawer are so spaced with respect to each other that when the drawer is withdrawn to the limit of its movement the stop-lugs c^3 engage 30 the shoulder a , and the stop-lugs c^2 engage the forward margins of the hooks D and limit the movement of the said drawer before the rear end thereof has passed beyond the forward end of its compartment. As 35 herein shown, the weight of the drawer and its contents is supported upon the horizontal partition A^3 , and said drawer-supporting devices constituting my invention are not brought into use until the drawer is 40 pulled outwardly past its longitudinal center line and thence to its limit of movement.

When the drawer is drawn outwardly to open the same, the outward movement thereof 45 is limited by the stop-lugs c^3 being brought into contact with the shoulders a of the grooves A^4 and the stop-lugs c^2 being brought against the side margins of the hooks D . The rear end of the drawer is at this time completely withdrawn from its compartment and 55 is therefore in position for papers or other articles in the rear end of the drawer to be readily consulted. In closing the drawer the bars C are forced entirely into the grooves 60 A^4 , being forced thereinto either by engagement of the outer ends of the bars with the lateral flanges on the front end of the drawer, as shown in Fig. 2, or by engagement of the hooks D with the shoulders between the larger 65 and smaller parts of the bars. When the drawer is closed, the hooks D pass into the forward ends of the grooves A^4 , and the thick-

ness of the supporting-hooks is slightly less than that of the parts c constituting the rear enlarged ends of the bars, so that said hooks 70 may pass freely into the grooves A^4 without contact with the end margins of said side walls.

The construction shown is applicable for all kinds of drawers to enable the same to be 75 freely opened to permit access to the drawer throughout its length. Said construction is, however, particularly applicable for use in connection with drawers for filing-cabinets wherein the papers to be filed are contained 80 in folders which are placed edgewise or vertically in drawers. In such filing devices the drawers are filled from front to rear with said folders, each folder occupying a permanent place in the drawer, and in order to 85 readily consult the rearmost folders the drawer must be fully opened. If no means be provided for supporting the drawer in its open position, the outer end thereof needs to be sustained in a horizontal position by 90 the use of one hand of the person consulting the files, and there is great liability of the drawer being pulled too far outwardly and falling out of its compartment. Moreover, when the drawer is supported as herein shown 95 both hands of the person using the same are free to be employed for consulting the files.

If it be desired to completely detach the drawer from a cabinet, desk, or the like of which it forms a part, this may be readily 100 done by pulling the drawer outwardly to its limit and raising the front end thereof, as shown in dotted lines in Fig. 1, to detach the hooks from the supporting-bars, the drawer being at this time free to be lifted or detached 105 from its supports. The operation of replacing the drawer on the supporting-bars is obviously the reverse of the detaching operation just described.

An important advantage of the construction shown is that the supporting devices do not necessitate providing spaces between the drawer and the side walls of the compartment, the side walls of the drawer being adapted to fit closely between the side walls of the compartment, as in the construction of ordinary 115 drawers. The supporting devices add but little to the cost of the construction of which the drawer or drawers constitute a part, and said devices are so arranged as to afford ample strength for supporting heavy drawers.

It is obvious that many changes may be made in the structural details illustrated without departing from the spirit of my invention, and I do not wish to be limited to such 125 details except as hereinafter made the subject of specific claims. For instance, the guides or grooves which receive the supporting-bars may be made of metal and set into and fastened in grooves in the side walls of 130 the compartment made to receive the same.

I claim as my invention—

1. Means for supporting a drawer in its open position comprising in combination with the

drawer and its compartment, the side walls of which compartment are provided with longitudinal grooves having stop-shoulders, supporting-bars located wholly outside of the plane of the outer faces of the side walls of the drawer and occupying and sliding in said grooves, means for slidably connecting the outer ends of the bars with said drawer, stops on said drawer, and stops in the front and rear ends of said bars which coact with said stops on the drawer and with those in the grooves for limiting the opening movement of the drawer.

2. Means for supporting a drawer in its open position comprising, in combination with the drawer having plain or unbroken side walls and its compartment, the side walls of which compartment are provided with longitudinal grooves, supporting-bars occupying said grooves and sliding endwise therein and hooks on the side walls of the drawer with which the outer ends of the bars have sliding and supporting engagement, said hooks being received by said grooves when the drawer is in its closed position.

3. Means for supporting a drawer in its open position comprising, in combination with the drawer and its compartment, the side walls of which compartment are provided with longitudinal grooves having stop-shoulders, supporting-bars occupying said grooves and sliding endwise therein, hooks on the side walls of the drawer with which the outer ends of the bars have sliding and supporting engagement, said hooks being received by said grooves when the drawer is in its closed position, and stops on front and rear ends of the bars adapted to engage respectively said hooks and said stop-shoulders in said grooves to limit the opening movement of the drawer.

4. Means for supporting a drawer in its open position comprising, in combination with the drawer and its compartment, the side walls of which compartment are provided with longitudinal grooves, supporting-bars located wholly outside of the outer planes of the side walls of the drawer and occupying said grooves, and sliding endwise therein, means for detachably and slidably connecting the forward ends of the bars with the drawer and stops on the bars for limiting the outward movement of the drawer, said drawer being detachable from the bars when the drawer occupies its outermost position by raising the outer end of the drawer upwardly from said bars.

5. Means for supporting a drawer in its open position comprising, in combination with the drawer and its compartment, the side walls of which compartment are provided with longitudinal grooves, stop-shoulders in said grooves, supporting-bars occupying said grooves and sliding endwise therein, downwardly-opening hooks on the side walls of the drawer with which the outer ends of the bars

have sliding and supporting engagement, and stops on front and rear ends of the bars, which coact respectively with said hooks and said shoulders in the grooves for limiting the outward movement of the drawer, said hooks being received by said grooves when the drawer is in its closed position and being adapted for disengagement with the bars, when the drawer occupies the outer limit of its movement, by raising the outer end of the drawer.

6. Means for supporting a drawer in its open position comprising, in combination with the drawer and its compartment, the latter provided with side walls with longitudinal grooves said drawer laterally filling said compartment, supporting-bars located wholly outside the planes of the outer faces of the side walls of the drawer and occupying and sliding endwise in said grooves, means for supporting the outer end of the drawer on said bars and stops on said bars for limiting the outward movement of the drawer.

7. Means for supporting a drawer in its closed position comprising, in combination with a drawer and its compartment, the latter being provided in its side walls with longitudinal grooves having stop-shoulders, supporting-bars having longitudinally-sliding engagement with said grooves, the inner ends of said bars being made wider and deeper than the outer ends thereof, hooks on the side walls of the drawer and engaging the smaller, outer ends of said supporting-bars, said hooks being received by said grooves when the drawer is closed, and stops on the front and rear ends of said bars adapted to engage respectively said hooks and the stop-shoulders in said grooves to limit the outward movement of said drawer.

8. Means for supporting a drawer in its open position comprising, in combination with a drawer and its compartment, the latter being provided in the side walls with longitudinal grooves having stop-shoulders, supporting-bars occupying said grooves, said bars comprising straight parts *c'* and strips *c* folded about the inner ends thereof to constitute the larger inner ends of said bars and which have close sliding engagement with the grooves, and hooks on the side walls of said drawer which are engaged by the outer ends of the parts *c'* of the bars, said hooks being made of a less thickness than the parts *c* of the bars, whereby said hooks may freely enter said grooves when the drawer is closed, and stops on the bars for limiting the outward movement of the drawer.

In testimony that I claim the foregoing as my invention I affix my signature, in presence of two witnesses, this 6th day of June, A. D. 1902.

FELIX TRAMBLAY.
